UNITED STATES PATENT OFFICE.

DANIEL EDWARDS, RICHARD LEWIS, AND PHILIP JONES, OF MORRISTON,
SWANSEA, ENGLAND.

APPARATUS FOR COATING PLATES WITH TIN.

SPECIFICATION forming part of Letters Patent No. 432,520, dated July 22, 1890.

Application filed October 26, 1889. Serial No. 328,833. (No model.) Patented in England May 16, 1887, No. 7,139, and in Spain September 15, 1888, No. 8,327.

To all whom it may concern:

Be it known that we, DANIEL EDWARDS, tin-plate manufacturer, RICHARD LEWIS, foreman, and PHILIP JONES, mechanic, subjects 5 of the Queen of Great Britain, all residing at the Dyffryn Iron and Tin-Plate Works, Morriston, Swansea, England, jointly have invented certain new and useful Improvements in Apparatus for Coating Metal Plates with Tin or 10 other Metal, (for which we have received Letters Patent in Great Britain, No. 7,139, dated May 16, 1887, and in Spain, No. 8,327, dated September 15, 1888,) of which the following is a specification.

15 In the specification of a former United States patent granted to us, No. 381,226, dated April 17, 1888, we described means whereby with a "tinning-pot" we were able to allow each plate which was to be coated to dwell at 20 rest for a time in the melted coating metal and yet to carry on the coating continuously and uniformly. We also described using with such apparatus a "dipping-pot" containing finishing coating metal, the plates being introduced into such dipping-pot by hand after 25 coming from the tinning-pot. According to our present invention we use a tinning-pot constructed as described in our former patent; but in place of using in conjunction therewith a dipping-pot into which the plates 30 have to be introduced by hand we so arrange the apparatus that the plates are passed without handling from the grease or flux bath at the exit end of the tinning-pot to and through 35 a secondary tinning-pot, the pair or pairs of rollers in which pot are completely immersed in coating metal at a lower temperature, preferably, than that in the first pot, and then the plates are caused to rise up from such second 40 pot through flux or grease contained in a bath above it.

The subject-matter claimed is hereinafter specifically designated.

45 The drawing hereunto annexed is a longitudinal section of apparatus constructed in the manner we prefer for carrying out our invention.

50 A is the tinning-pot containing the melted coating metal. B is the grease or flux bath above it.

C is the rack of curved guide-bars, into the

spaces between which the plates to be coated are inserted, one plate into each space. The rack is shown to be formed to receive three plates, so that two plates may be at rest in 55 the bath of melted metal while the third is being pushed forward to the withdrawing-rolls D in the grease or flux bath B.

So far the apparatus is the same as is described in the specification of our former patent, except that the two pairs of rolls D, instead of being, as before, placed nearly vertically one pair above the other, are now in a more inclined position. As the plates emerge from between the upper pair of rolls, 60 they pass below curved guide-bars E, which bend them downward and conduct them to the nip of a pair of rolls F, which are completely immersed in melted coating metal contained in the "dipping" or "finishing" pot 70 G. It is necessary that the rolls F should be entirely immersed in the melted metal; otherwise "scruff" or "dross" floating on the surface of the metal will tend to adhere to the rolls, and then all plates as they pass between 75 the rolls will be marked by the patches of scruff or dross which are on the plates, and imperfect work result. As the plates pass from the rolls F, they come against curved 80 guide-bars H, which bend them again upward and lead them to the lowest pair of rolls I, by which the plates are carried upward through grease or flux contained in a grease-pot K, which rests upon the top of the pot G. Preferably the lowest pair of rolls I are made 85 to dip into the melted metal.

The trains of toothed wheels for driving the several pairs of rolls are shown by dotted circles. The wheels for driving the rolls D and F receive motion by worm and worm-wheel gearing from the driving-shaft L. It will thus be seen that by our improved apparatus we are enabled simultaneously to immerse several plates directly in the tinning-bath, so that some may rest there and become thoroughly coated while others are being fed through the succeeding baths.

We are aware that it is old to feed single plates through fluxing and coating baths between rollers immersed therein, and do not, 90 therefore, broadly claim so doing.

Having thus fully described the organiza-

tion and operation of our improved apparatus for coating metal plates with tin or other metals, what we claim therein as new and of our own invention is—

1. The combination, substantially as hereinbefore set forth, of a tinning-pot, a rack of parallel guide-bars fixed therein adapted simultaneously to hold several plates side by side and subject to the action of the coating metal, a flux-box above the tinning-pot, two or more pairs of withdrawing-rolls in the flux-box, a dipping or finishing pot, feed-rolls completely immersed therein, and continuous arched guide-bars extending from just above the withdrawing-rolls to just above the feed-rolls and adapted to conduct the plates directly from the one to the other.
2. The combination, substantially as hereinbefore set forth, of a tinning-pot, a rack of parallel guide-bars fixed therein adapted simultaneously to hold several plates side by side and subject to the action of the coating metal, a flux-box above the tinning-pot, two or more pairs of withdrawing-rolls in the flux-box, a dipping or finishing pot, feed-rolls completely immersed therein, continuous arched guide-bars extending from just above the withdrawing-rolls to just above the feed-rolls,

a flux-box above the finishing-pot, a second pair of rollers in said pot, a guide in the finishing-pot adapted to conduct the plates from one pair of rolls to the other, both the guide and rolls being beneath the normal surface of the metal melted in the pot, and two or more pairs of rolls in the second flux-box, (arranged one pair over the other beneath the level of the flux,) between which rollers the coated plates pass.

DANL. EDWARDS.
RICHD. LEWIS.
PHILIP JONES.
